UNITED STATES PATENT OFFICE.

JOHN E. SCHENCK, OF CHICAGO, ILLINOIS, ASSIGNOR TO AMERICAN CAN COMPANY, OF NEW YORK, N. Y., A CORPORATION OF NEW JERSEY.

POURING-NOZZLE CLOSURE FOR CANS.

1,215,997.

Specification of Letters Patent. Patented Feb. 13, 1917.

Application filed June 14, 1909. Serial No. 502,076.

To all whom it may concern:

Be it known that I, JOHN E. SCHENCK, a citizen of the United States, residing in Chicago, in the county of Cook and State of Illinois, have invented a new and useful Improvement in Pouring-Nozzle Closures for Cans, of which the following is a specification.

My invention relates to the construction 10 of cans having pouring nozzles.

Heretofore cans with pouring nozzles for containing syrup and other like articles have usually been furnished with screw cap closures, and considerable difficulty and annoyance is often experienced in removing the screw caps owing to the screw threaded cap sticking fast, especially when the can is filled with syrup or other gummy or sticky material liable to harden. And if the screw 20 threads in the sheet metal nozzle and sheet metal cap are misformed or become slightly distorted, difficulty is also experienced in turning the screw cap down sufficiently to cause it to properly and effectually clamp 25 the gasket or sealing disk which is interposed between the nozzle and screw cap to seal the can liquid tight.

The object of my invention is to provide a simple and efficient construction of pouring nozzle closure for syrup and other cans 30 which may be cheaply manufactured, which will serve to securely close the can liquid tight with certainty and reliability, and which at the same time may be readily 35 opened.

My invention consists in a syrup or other can having a smooth, drawn sheet metal pouring nozzle provided with an inturned flange at its upper edge forming a gasket 40 seat in connection with an outside fitting seamless friction closure cap having a seat on the inside to receive the sealing gasket, and an external rolled rim at its lower edge to strengthen and stiffen the same and afford 45 a pry-off rim for removing the outside fitting friction closure cap, the can itself having a fulcrum rim adjacent to the pouring nozzle, and the interengaging friction seat walls of the nozzle and cap serving to 50 hold the cap securely in place and the gasket firmly compressed between the nozzle and cap when the cap is forcibly driven home on the nozzle.

In the accompanying drawing forming a 55 part of this specification, Figure 1 is a plan

view of a pouring nozzle can embodying my invention. Fig. 2 is a central vertical section on line 2—2 of Fig. 1, and Fig. 3 is a fragmentary top plan view with the cover removed.

In the drawing, A represents the body of the can, B the top head, C the bottom head, D the pouring nozzle and F the outside fitting friction cap closure therefor and G the interposed gasket or sealing disk. The body 60 A of the can may be of any suitable shape, preferably rectangular. The top head B is furnished with an upwardly projecting marginal flange b which fits inside the upper end of the body A, and a depending flange b¹ surrounding and embracing the upper end of the body of the can which fits in the channel or groove formed by the top head flanges b b¹. The marginal flanges b b¹ of the head B, in connection with the end of 65 the body constitute a fulcrum rim for removing the outside friction cap closure F from the nozzle D.

The top head B is also preferably furnished with an upwardly projecting flange b² surrounding the small pouring opening B¹ therein. The pouring nozzle D is a smooth, drawn seamless sheet metal cylindrical shell and surrounds at its lower end the upturned flange b² of the top head to which 70 it is securely soldered. The pouring nozzle D is provided at its upper end with an integral seamless inwardly projecting flange d, the same being preferably furnished with an annular bead or shoulder d¹ to afford an 75 efficient sealing seat or bearing against the gasket G which is interposed between the outside friction cap F and the nozzle D.

The outside fitting friction closure cap F is a seamless drawn sheet metal shell of 80 cylindrical form and has an interior friction seat wall f adapted to tightly and snugly engage the exterior friction seat wall d² of the nozzle D and to hold the cap securely on the nozzle by frictional 85 engagement when it is pressed home. The outside fitting friction closure cap F has an external stiffening or strengthening roll f¹ at its lower edge which also serves as a pry-off rim for removing the friction cap F. 90 The friction cap F is preferably furnished with an annular gasket seat or channel f² at its upper end, the same conforming generally in cross section to the raised shoulder or bead d¹ of the annular flange d of the 95 100 105 110

nozzle D. The gasket or sealing disk G is preferably annular and is securely clamped and held between the outside fitting friction cap F and nozzle D by the tight frictional engagement of the cap and nozzle when the cap is forced home on the nozzle.

I claim:

1. A pouring nozzle can having an up-standing stiffened rim at the edge of the top 10 of the body and at the end of the top of the body adjacent said stiffened rim and spaced inwardly therefrom, a pouring nozzle of relatively small diameter extending upwardly from the top of said body and above 15 said stiffened rim a substantial distance, said nozzle having a cylindrical non-tapering exterior friction wall and an inwardly extending flange at the top thereof, a cap for said nozzle having a non-tapering internal 20 friction wall of length sufficient to bring its bottom edge below the upper edge of said stiffened rim, said lower edge being bent back upon itself to stiffen said cap and to provide with said stiffened rim means for 25 engaging an opening tool, and a gasket arranged between the flange on the pouring nozzle and the top of said cap.

Copies of this patent may be obtained for five cents each, by addressing the "Commissioner of Patents, Washington, D. C."

2. A pouring nozzle can having an up-standing stiffened rim around the end of the 30 can body, and close to the rim of the top of the body and spaced inwardly therefrom a pouring nozzle of relatively small diameter extending upwardly from the top of said body and above said stiffened rim a substantial distance, said nozzle having a cylindrical non-tapering exterior friction wall and an inwardly extending flange at the top thereof, a cap for said nozzle having a non-tapering internal friction wall of length 35 sufficient to bring its bottom edge below the upper edge of said stiffened rim, said lower edge being bent back upon itself to stiffen said cap and to provide with said stiffened rim means for engaging an opening tool, and a gasket arranged within the friction 40 wall of the cap between the flange on the pouring nozzle and the top of the said cap, the friction wall of the cap at its upper end being extended directly inward to engage 45 above said gasket.

JOHN E. SCHENCK.
